United States Patent Office

Des. 225,502
Patented Dec. 19, 1972

225,502

INTERROGATION APPARATUS CARREL

Walter M. Miller, Arlington Heights, Ill., assignor to
Medequip Corporation

Filed Nov. 18, 1970, Ser. No. 26,060

Term of patent 14 years

Int. Cl. D6—04

U.S. Cl. D6—181

FIG. 1 is a perspective of an interrogation apparatus barrel incorporating the design;

FIG. 2 is a reduced top plan thereof;

FIG. 3 is a front elevation thereof;

FIG. 4 is a reduced elevation looking from the right of FIG. 3;

FIG. 5 is a reduced rear elevation; and

FIG. 6 is a fragmentary, reduced vertical section taken along lines 6—6 of FIG. 1.

The left side is a mirror image of the right side, FIG. 4.

I claim:

The ornamental design for an interrogation apparatus barrel, as shown and described.
